UNITED STATES PATENT OFFICE.

EDWIN WELLINGTON MAYFIELD, OF CHICAGO, ILLINOIS; GOUDY MAYFIELD ADMINISTRATOR OF SAID EDWIN WELLINGTON MAYFIELD, DECEASED.

TELEGRAPHIC RECEIVER.

1,266,841.

Specification of Letters Patent. Patented May 21, 1918.

Application filed May 29, 1916. Serial No. 100,456.

To all whom it may concern:

Be it known that I, EDWIN WELLINGTON MAYFIELD, a citizen of the United States, residing at Chicago, in the county of Cook and State of Illinois, have invented a certain new and useful Improvement in Telegraphic Receivers, of which the following is a full, clear, concise, and exact description, reference being had to the accompanying drawings, forming a part of this specification.

My invention relates to telegraphy and more particularly to a telegraphic receiver. Broadly the object of my invention is to provide improved means for receiving telegraphic signals with speed and secrecy and at a minimum of discomfort to the receiving operator.

There is a general demand for speed and secrecy for receiving certain classes of telegraphic communications, particularly for receiving telegrams in hotels, brokers' offices and other public or semi public places.

It has been proposed heretofore to employ the ordinary telephone receiver directly in the receiving circuit of the telegraph as a sounder. I find that this is wholly impractical due to the intense sharpness of the makes and breaks of currents and the painful effect upon the ear of the operator. The telephone receiver is relatively a very sensitive and powerful instrument responding strongly to current changes of infinitesimal magnitude. As the receiver would, in practice, be necessarily clamped upon the ear of the user in order to render the signals secret, a powerful response of the receiver to the sharp telegraphic impulses would produce a condition that would be wholly unbearable. Not only is the wave front of a telegraphic impulse excessively sharp, but also the energy of the current is too great to be permitted to operate directly upon the diaphragm of the receiver. The sounds of the breaks are as intense and sometimes more so than those of the makes and the signals are indistinguishable as so received. In addition the sharp making and breaking of the currents are accompanied by high frequency vibration or overtones that are distinctly unpleasant.

I have, according to my invention, interposed means for diminishing the effect of the telegraphic impulses upon the diaphragm of the receiver and particularly for screening out such vibrations as are unnecessary to an

understanding of the telegraphic signal and such other vibrations or overtones as are unpleasant to the ear. This produces a resulting vibration which is surprisingly intelligible and at the same time is pleasant to the ear.

The particular means that I may employ to secure this screening effect will now be described in connection with the accompanying drawings which illustrate one embodiment of my invention. It is to be understood that I do not intend to be limited to the precise details shown or described, and that the dimensions and proportions are not of the essence of the invention except as the same are set out in the accompanying claims.

Figure 1 is a diagram of the circuit employed in connection with my invention;

Fig. 2 is a side elevation of the means for transferring the signal impulses from the telegraphic circuit to the telephone circuit with the casing shown in section;

Fig. 3 is an end elevation of the microphonic device and

Fig. 4 is a cross section taken on the line 4—4 of Fig. 2.

I have found that in receiving telegraphic impulses it is essential to receive the sharp staccato sound of the bar striking upon the anvil when the circuit is made, but that it is not so essential to receive the sound of the bar or striker moving against the stop. In other words, if the sound of the make in the telegraphic circuit is clearly transmitted, signals are readily intelligible even though the sound of the break is greatly reduced. In carrying out my invention I provide the usual or any preferred telegraph sounder giving the conventional signal upon the usual make and break in the telegraph circuit and employing a sensitive device such as a microphone tuned particularly to the sound of the bar striking the anvil for a make in the telegraphic circuit. To this end I employ the sounder 1 connected in the telegraph circuit 2 which is provided with a suitable key or other circuit controlling device 3 and a suitable source of current 4.

I place a microphonic device 5 in the immediate vicinity of the sounder 1 so that the microphonic device will be responsive to the sound emanating from the sounder 1. The microphonic device 5 is included serially in a telephone circuit 6 which may be directly connected to the receiver 7 or may

be connected thereto through the interposition of an induction coil, as illustrated. The microphonic device 5 is supplied with suitable current from a source of current 9 which, in the diagram of Fig. 1, I have illustrated as the usual telegraph dynamo. It is to be understood that a battery may be employed instead as it is obvious that a direct current battery provides ideal current for the operation of a microphone.

As a suitable battery is not always available and as telegraph instruments are generally operated upon dynamo currents I have shown the dynamo 9 in series with suitable inductance coils 10 and 11, as taking the place of a battery. A condenser 12 is connected around the inductance coils 10 and 11 and the source of current 9. As the microphonic device 5 is tuned to the particular frequency of the sound emanating from the sounder when the circuit is closed, and as this sound is of a higher frequency than the sound which emanates from the device when the striker moves against the backstop, I find that it is possible to adjust the capacity of the condenser 12 so as to aid in the transmission of sounds of the desired frequency and to screen out sounds of a lower frequency. The telegraph instrument that I have shown in Fig. 1 is provided with a pivoted striker bar 15 adapted when the circuit is closed through the coil 17 to strike the anvil 16 by attraction of the armature 18, which is secured to the bar or striker 15. The usual spring 19 is provided for moving the striker bar 15 against the usual backstop 20. A suitable baseboard 21 is provided for supporting both the microphonic device 5 and the sounder 1. The baseboard 21 is preferably of a non-resilient material and layers of felt 22-23 or similar material are interposed between the two devices and the baseboard in order that a minimum of sound-transmission through the baseboard shall occur. A suitable cover 24 is provided for housing the sounder 1 and the microphonic device 5, this housing or cover being preferably, though not necessarily, lined with felt or other non-resilient material in order to prevent sound waves being transmitted therethrough. The microphonic device 5 comprises a base member 25 upon which are supported the diaphragm posts 26 and 27 and the back electrode posts 28. A granular carbon button 29 has its stem 30 secured in the post 28 by means of a set screw 31. The post 28 is preferably insulated from the base plate 25. The posts 26 and 27 have a strip of sheet metal 32 secured to them and these posts are relatively adjustable in order to place the sheet 32 under suitable tension in order to tune the same to the desired frequency of vibration.

I have shown the post 27 as being sup-

ported in a dove-tailed slot 33 in the base plate 25. Suitably screw-threaded rods or posts 34 and 35 are provided with wing nuts 36 for placing the sheet 32 under proper tension. Suitable lock nuts 37 may be provided for maintaining the adjustment.

The metal strip 32 which serves as a tuned reed or tuned diaphragm is provided with a slot 38 for the attachment of a front electrode of the granular button 29. As above mentioned, the metal sheet 32 is tuned as closely as possible to the dominant frequency of the sound which is emitted when the striker engages the anvil 16. As this is generally of a higher frequency than the sound which is given off when the striker engages the backstop 20, I am enabled to transmit a sharp staccato sound to the head telephone 7 which is clamped to the ear of the operator.

I am familiar with numerous attempts in the prior art to obtain telephonic transmission of telegraph signals. These devices are unsatisfactory, both on account of the confusion which results between the sound of a make and the sound of a break and because of the extraneous vibrations which are introduced and which prove highly annoying and unpleasant to the operator; particularly under continuous usage.

Inasmuch as I have found and have set forth that the best transmission is obtained by having the telephonic transmission device tuned to the fundamental frequency of the sound which is given off upon makes in the telegraphic circuit and less responsive to the break in that circuit, I consider it within the scope of my invention to arrange the telegraphic sounder to strike distinctive tones such as may be obtained by reeds or the like so that when the armature of the sounder is attracted, a different distinctive tone is emitted than when the armature is retracted.

What I claim is:

1. In combination a telegraph sounder, a microphonic device, a casing inclosing said sounder and said device, a telephone receiver operatively connected to said microphonic device and means for rendering said telephone receiver particularly responsive to certain ones only of the sounds emanating from said telegraphic sounder.

2. In combination a telegraphic circuit having means therein to make and break the current, a telephone receiver isolated from but influenced by the make and break in said telegraphic circuit and means for rendering said telephone receiver responsive in greater degree to the make than to the break in said telegraphic circuit.

3. In combination a telegraphic circuit having means adapted to make and break the current therein, a telephone receiver and means to cause said receiver to respond vig-

orously to the makes in the circuit and to respond less vigorously for breaks in said circuit.

4. In combination a base, a standard, a microphone electrode secured to said standard, a pair of standards adjustable relative to each other secured to said base, a thin sheet of metal secured to said standard, said sheet of metal being connected to the co-operating electrode of said microphonic device, a telegraph sounder supported adjacent said sheet of metal and adapted to vibrate said sheet of metal through the air only and a substantially sound proof shell inclosing said sounder and said sheet of metal.

5. In combination, a telegraphic sounder,

a base, a pair of laterally adjustable standards on said base, a third standard arranged adjacent first said standards, a microphone carried by said first standard, a strip of metal extending between first said standards and connected thereto, said microphone having mechanical connection with said strip at its intermediate portion, means to adjust said standards to regulate the responsiveness of said strip to various sound frequencies, and a hood to confine and direct the sounds from said telegraphic sounder to said strip.

In witness whereof, I hereunto subscribe my name this 26th day of May, A. D. 1916.

E. WELLINGTON MAYFIELD.
